UNITED STATES PATENT OFFICE.

WILLIAM D. CARNAL, OF AKRON, OHIO, ASSIGNOR TO WESTERN TIRE COMPANY, OF OMAHA, NEBRASKA, A COPARTNERSHIP.

DESIGN FOR A TIRE TREAD.

Application filed September 7, 1922. Serial No. 3,644. Term of patent 3½ years.

To all whom it may concern:

Be it known that I, WILLIAM D. CARNAL, a citizen of the United States, residing at Akron, in the county of Summit and State of Ohio, have invented a new, original, and ornamental Design for Tire Tread, of which the following is a specification, reference being had to the accompanying drawing, forming a part thereof.

Fig. 1 is a plan view of a segment of a tire tread, and:

Fig. 2 is a cross section of the same, the

view being taken along the line 2—2 of Fig. 1.

I claim:

The ornamental design for a tire tread, as shown.

In testimony whereof, I have affixed my signature in presence of two witnesses.

WILLIAM D. CARNAL.

Witnesses:

CHARLES A. McLAUGHLIN,
C. B. WILLIAMSON.
